DOOR LOCK

Algott L. Nelson, Detroit, Mich., assignor to
Ternstedt Manufacturing Company, Detroit,
Mich., a corporation of Michigan

Application January 22, 1940, Serial No. 314,944

9 Claims. (Cl. 292—164)

This invention relates to a door lock and more particularly a door lock for an automobile door.

It is an object of this invention to produce a lock which permits the use of a narrow door lock pillar. This object is achieved by arranging the bolt so that it is retracted by power stored up during the opening of the door thereby obviating the need for the usual outside door handle spindle which cuts across the door and through the pillar outside the path of travel of the sliding window glass.

It is also an object of this invention to produce an automobile door lock which can be easily operated from without the door by a flush door handle or push button thereby obviating the need for the conventional swinging handle which projects from the outside face of the door.

In the drawings:

Fig. 1 is a fragmentary view of the outside face of an automobile door and the adjacent hinge pillar with a detail showing of the lock.

Fig. 1' is a fragmentary view showing the lock bolt, striker and outside door handle.

Fig. 2 is a section along the line 2—2 of Fig. 1.

Fig. 3 is a section along the line 3—3 of Fig. 1.

Fig. 4 is a view along the line 4—4 of Fig. 1.

Fig. 5 is a detail showing connections between the outside handle and the toggle.

Referring more particularly to the drawings there is shown a door 1 hinged at its forward edge to the body hinge pillar 2. In Fig. 1 the outside door panel 3 has been broken away to show the lock in elevation.

The lock comprises a bolt 4 arranged to interengage striker 5 mounted on the body pillar 6. The bolt is retracted by a draft link 7 having a lost motion connection with the bolt 4 in the form of a pin 8 fixed to the bolt which engages link 7 in the elongated slot 9.

The remote end of the link 7 is pivotally connected by pin 10 with lever 11. The lever 11 is pivotally mounted on plate 12 by pin 13. The upper end of lever 11 is pivotally connected by pin 14 to plate 15 which is hinged by means of pin 16 to toggle link 17. Toggle link 17 is hinged by means of pin 19 with toggle lever 18. Toggle lever 18 is hinged by pin 20 to plate 21 which is fixed by means of rivet 22 to the inner sheet metal door panel 23. Toggle 17, 18 is biased to over center position by spring 24 carried on pin 16. Toggle 17, 18 is broken by push button 25 acting against pin 19. Push button 25 is held in retracted position by coil spring 26.

A convolute spring 27 is fixed to plate 12 as at 28 and has its free end 29 hooked over stud 30

on link 7. It is proposed to energize or load coil spring 27 during the initial opening movement of the door 1. To this end a slide plate 31 is slidably mounted along the lower edge of plate 12 and guided along its side faces by plates 33 and 34 which are welded or otherwise fixed to the lower edge of plate 12. The slide 31 is yieldably held against the lower edge 32 of plate 12 by tension coil spring 35 which has its upper end 36 hooked into bracket 37 turned out of plate 12 and its lower end 38 hooked into lug 39 fixed to slide 31.

The operation of this lock is as follows: As shown in the full lines in Figs. 1, 2 and 5, the bolt is projected, the toggle 17, 18 made, thereby acting through lever 11 and pin 30 to hold the spring 27 in compression. To retract the bolt the push button 25 is pushed in to break the toggle 17, 18, dotted line showing Fig. 2. This releases link 7 so that the spring 27 is free to unwind thereby moving link 7 and lever 11 to the left, dotted line showing Fig. 1, which retracts the bolt. It will be noted that when the bolt is retracted and the door closed, the rounded lower corner 40 of lever 11 is positioned against shoulder 41 of slide 31. As the door opens, slide 31 moves to the left relative to plate 12, as viewed in Fig. 1. As the slide 31 moves to the left, shoulder 41 engages toe 40 thereby swinging lever 11 clockwise, which moves link 7 and bolt 4 to projected position and at the same time energizes or compresses spring 27. As the lever 11 moves clockwise, it also returns the toggle 17, 18 to made position which holds the lever 11 in its original position until again released through push button 25. This action occurs during the initial opening movement of the door. As the door is swung further open to fully open position the rounded toe 40 of the lever 11 slides along the top edge 32 of slide 31 until the rubber bumper 42 abuts the door hinge pillar 43 checking further opening of the door. As the door swings closed, rounded toe 40 of the lever 11 slides back over the upper edge 32 of slide 31 and bolt 4 rides over and interengages striker 5.

It will be noted that after the door has been swung open sufficiently to swing lever 11 clockwise to stress spring 27 and make toggle lever 17, 18, which is hereinafter referred to as the "set" position of lever 11, that upon further opening of the door rounded toe 40 slides along upper edge 32 of slide 31. Because of this, after the lever 11 is set it cannot be released and the bolt retracted until the door is again swung nearly closed, that

is, until the rounded toe 40 of the lever again passes to the left of shoulder 41, Fig. 1.

The bolt 4 is projected by the conventional convolute spring 50. To retract the door from the outside, the outside handle 51, pivoted as at 52, is swung outwardly which draws the draft link 53 in the direction of the arrow (see Fig. 5). The draft link 53 swings the bell crank 54 counterclockwise, Fig. 5, thus moving the pin 19 and the toggle 17, 18 outwardly past center to break the same. This releases the energy stored in spring 27 which retracts the bolt 4. Spring 27 is stronger than spring 50 so that as the bolt 4 is retracted, spring 50 is loaded or wound up.

The door is provided with a pivoted panel 56 and a sliding panel 57, such as described in the Fisher Patent No. 2,048,605. The link 53 will be located on the outside of the sliding panel 57 and will connect with the bell crank 54 beneath the pivoted panel 56.

I claim:

1. In an automotive vehicle body having a door opening, and a door hinged along an edge of said opening, the combination of a door latch adapted for mounting on said door comprising a retractable latch bolt, a support plate, energy storing means mounted on the support plate, means connecting said energy storing means with said bolt, a lever operatively connected with said energy storing means, draft means adapted for connection to a fixed part of the body, and a lost motion connection between the draft means and the lever operable during a portion of the door opening movement to swing said lever to set the same and store energy in said energy storing means, and manually controlled means for releasably locking the lever in set position operable to release said lever whereby the energy in said energy storing means is utilized in retracting the bolt.

2. In an automotive vehicle body having a door opening and a door hinged along an edge of said opening, the combination of a door latch adapted for mounting on said door comprising a retractable latch bolt, a support plate, energy storing means mounted on the support plate, means connecting said energy storing means with said bolt, a lever operatively connected with said energy storing means, draft means adapted for connection to a fixed part of the body, and a lost motion connection between the draft means and the lever operable during a portion of the door opening movement to swing said lever to set the same and store energy in said energy storing means, a toggle one end of which is connected to the support plate and the other end of which is connected to said lever for releasably locking the lever in set position and operable to release said lever whereby the energy in said energy storing means is utilized in retracting the bolt.

3. In an automotive vehicle body having a door opening and a door hinged along an edge of said opening, the combination of a door latch adapted for mounting on said door comprising a retractable latch bolt, a support plate, energy storing means mounted on the support plate, means connecting said energy storing means with said bolt, a lever operatively connected with said energy storing means, draft means adapted for connection to a fixed part of the body and movable relative to the support plate as the door swings, an abutment on said draft means engageable with the lever during the initial portion of the opening movement to swing the lever

to set position and energize the energy storing means whereupon the lever swings clear of the abutment during the remainder of the swinging movement of the door, and manually controlled means for releasably locking the lever in set position operable to release said lever whereby the energy in said energy storing means is expended to retract the bolt.

4. In an automotive vehicle body having a door opening and a door hinged along an edge of said opening, the combination of a door latch adapted for mounting on said door comprising a retractable latch bolt, a support plate, energy storing means mounted on the support plate, means connecting said energy storing means with said bolt, a lever operatively connected with said energy storing means, draft means adapted for connection to a fixed part of the body and movable relative to the support plate as the door swings, an abutment on said draft means engageable with one end of the lever during the initial portion of the opening movement of the door to swing the lever to set position and energize the energy storing means whereupon the lever swings clear of the abutment during the remainder of the swinging movement of the door, a toggle one end of which is connected to the support plate and the other end of which is pivotally connected to the other end of the lever for releasably locking the lever in set position, and breakable to release said lever whereby the energy in said energy storing means is utilized in retracting the bolt.

5. In an automotive vehicle having a door opening and a door hinged along an edge of said opening, the combination of a door latch adapted for mounting on said door comprising a retractable latch bolt, a support plate, a spring mounted on the support plate, a connection between said spring and said bolt, a lever operatively connected with said spring, draft means adapted for hinging to the edge of the door opening including a member slidable along the said support plate during the hinging movement of the door, a shoulder on said member engageable with an end of said lever during the initial portion of the opening movement of the door to set the lever and stress the spring, and manually controlled means for releasably holding the lever in set position and operable to release the lever whereby the energy stored in the spring is expended in retracting the bolt.

6. In an automotive vehicle having a door opening and a door hinged along an edge of said opening, the combination of a door latch adapted for mounting on said door comprising a retractable latch bolt, a support plate, a spring mounted on the support plate, a connection between said spring and said bolt, a lever operatively connected with said spring, draft means adapted to be hinged to the edge of the door opening including a member slidable along the said support plate during the hinging movement of the door, a shoulder on said member engageable with an end of said lever during the initial portion of the opening movement of the door to set the lever and stress the spring, manually controlled means for releasably holding the lever in set position and operable to release the lever whereby the energy stored in the spring is expended in retracting the bolt, the end of said lever clearing said shoulder upon reaching set position whereupon the said end of the bolt slidably engages the upper edge of the member whereby the manually controlled

means is rendered ineffective to release the lever.

7. In an automotive vehicle having a door opening and a door hinged along an edge of said opening, the combination of a door latch adapted for mounting on said door comprising a retractable latch bolt, a support plate, a spring mounted on the support plate, a connection between said spring and said bolt, a lever operatively connected with said spring, draft means adapted to be hinged to the edge of the door opening including a member slidable along the said support plate during the hinging movement of the door, a shoulder on said member engageable with an end of said lever during the initial portion of the opening movement of the door to set the lever and stress the spring, manually controlled means for releasably holding the lever in set position and operatable to release the lever whereby the energy stored in the spring is expended in retracting the bolt, the end of said lever clearing said shoulder upon reaching set position whereupon the said end of the bolt slidably engages the upper edge of the member whereby the manually controlled means is rendered ineffective to release the lever, and resilient means for yieldably holding the sliding member in engagement with the lower end of the said lever.

8. In an automotive vehicle body having a door opening and a door hinged along an edge of said opening, the combination of a door latch adapted for mounting on said door comprising a retractable latch bolt, a support plate, a spring mounted on the support plate, draft means connecting said spring with said bolt, a lever pivotally mounted on said support plate and pivotally connected to said draft means, a draft link adapted to

be pivotally connected to the body at the hinging edge of said opening, a plate pivotally connected to the inner end of said draft link and slidable along the support plate, said plate having a notch therein to provide a shoulder for engagement with an end of the lever during a portion of the opening movement of the door to set the lever, and said plate having a raised surface along which the said end of the lever slides during the remaining portion of the opening movement of the door whereby the set lever cannot be released.

9. In an automotive vehicle body having a door opening and a door hinged along an edge of said opening, the combination of a door latch adapted for mounting on said door comprising a retractable latch bolt, a support plate, a spring mounted on the support plate, draft means connecting said spring with said bolt, a lever pivotally mounted on said support plate and pivotally connected with said draft means, a draft link adapted to be pivotally connected to the body at the hinging edge of said opening, a plate pivotally connected to the inner end of said draft link and slidable along the support plate, said sliding plate having a notch therein to provide a shoulder for engagement with an end of the lever during a portion of the opening movement of the door to set the lever, and said sliding plate having a raised surface along with the said end of the lever slides during the remaining portion of the opening movement of the door whereby the set lever cannot be released, and resilient means connecting the sliding plate and support plate whereby the sliding plate yieldably engages the end of said lever.

ALGOTT L. NELSON.
